UNITED STATES PATENT OFFICE.

KASPER H. SCHAPER, OF LINN'S MILLS, MISSOURI.

COUNTING-REGISTER.

SPECIFICATION forming part of Letters Patent No. 423,880, dated March 18, 1890.

Application filed June 5, 1889. Serial No. 313,199. (No model.)

To all whom it may concern:

Be it known that I, KASPER H. SCHAPER, of Linn's Mills, Lincoln county, Missouri, have made a new and useful Improvement in Registers, of which the following is a full, clear, and exact description.

The improvement consists substantially as is hereinafter set forth and claimed, aided by the annexed drawings, making part of this specification, in which—

Figure 1 is a face view of the improved register; Fig. 2, a section on the line 2 2 of Fig. 4; Fig. 3, a longitudinal section on the line 3 3 of Fig. 2; Fig. 4, a transverse section on the line 4 4 of Fig. 2; and Figs. 5 and 6, views analogous to that of Fig. 2, but showing, respectively, different means for operating the register.

The same letters of reference denote the same parts.

A represents the register-case.

B represents the units-wheel. It is fastened to the shaft C, Figs. 1, 2, and 4, which is journaled in the back a of the case, and its outer end projects through the front a' of the case, and upon the outer end are journaled successively the tens-wheel D and the hundreds-wheel E, substantially as shown in Fig. 4.

The units-wheel B can be operated by any suitable means. In Fig. 2 a longitudinally-reciprocating bar F, carrying a spring-pawl f, whose point engages with the ratchet b of the units-wheel, is the means for transmitting the motion to the units-wheel and causing it to rotate in the direction of the arrow x. Every stroke of the bar F causes the units-wheel to rotate a distance of one tooth, and twenty strokes of the bar effect the complete rotation of the units-wheel, and the shoulder b', Figs. 2 and 4, to encounter one of the cogs g of a gear G, Figs. 2 and 3. This gear G and another gear H are fastened to a shaft h, which is parallel with the shaft C and journaled in the case. The cogs g of the gear G are respectively opposite the spaces h' between the cogs h² of the gear H, substantially as shown in Fig. 2, in which figure the cogs g appear in broken lines. This relative arrangement of the cogs g and h² is essential to the proper working of the device. The continued rotation of the units-wheel after its shoulder b' has encountered the cog g causes the gears G

and H and shaft h to be rotated a distance of one cog. The gear H intermeshes with the teeth d of the tens-wheel D, Fig. 3, and this last-named wheel is thereby rotated on its bearing a distance of one tooth.

The gear H is provided with a projection h³, which extends into the plane of the hundreds-wheel E, Fig. 3, and when the gear H has been worked around one rotation the projection h³ causes it to engage with the hundreds-wheel E and effect the rotation thereof a distance of one of its teeth e.

All the described wheels or gears have ten teeth, saving the units-wheel, which has twenty teeth. The units, tens, and hundreds wheels are respectively provided with hands I J K, Figs. 1 and 3, which are carried around, respectively, with the wheels B D E, and are operated in connection with the dial-plate L, Fig. 1. Every time the wheel B is rotated one tooth its hand I moves one space l on the dial—that is, say, from 0 to the half-mark l'. Every time the tens or the hundreds wheel is rotated one tooth its hand moves two spaces l on the dial—that is, say, from 0 to 1. As the units-hand is within one space l of the 0 mark on the dial, and is moving over that space, the tens-hand moves two spaces, and when the units-hand is about to complete its tenth revolution and the tens-hand its first revolution the hundreds-hand moves two spaces l on the dial.

If it is desired to count above one thousand, a fourth wheel and hand are added to the register, together with suitable means substantially similar to what has been described in effecting the movement of the other wheels.

Suitable means—such as the pawls M M', Fig. 2—are employed to prevent the wheels from being jarred out of place or from turning backward.

In Figs. 5 and 6 the bars F' F², respectively, are pivoted, and the bar F' has one pawl f, and the bar F² has two pawls f for communicating the motion of the bar to the gear B. The action of the bars F' F² and pawls f is obvious, and the bars F' F² and pawls are substantially the equivalent of the bar F and pawl.

I claim—

The combination, in a register, of the shaft journaled in the casing, the units-wheel

mounted thereon and having twenty teeth and carrying the single shoulder b' , the reciprocating bar F, the spring-pawl f, moving the units-wheel one tooth at each reciprocation of the bar F, the gear-wheel G, having ten teeth and rotated by said shoulder b' , the toothed wheel H, having ten teeth, mounted on the same shaft as the gear-wheel G, turning therewith, and provided with a single projection h^3 , the gears G and H arranged with the cogs or teeth of one opposite the spaces between the cogs of the other, the tens-wheel D, having ten teeth, mounted loosely on the same wheel as the units-wheel, the hundreds-

wheel E, having ten teeth, mounted loosely on the hub of the tens-wheel and rotated by the projection h^3 on the wheel H, the spring-pawls or detents M M', and the indicator-hands I J K, respectively moved by the units, tens, and hundreds wheels, substantially as specified.

Witness my hand this 27th day of May, 1889.

KASPER H. SCHAPER.

Witnesses:
